UNITED STATES PATENT OFFICE.

CARL WITTKE, OF COLUMBUS, OHIO.

FLUE-CUTTER.

SPECIFICATION forming part of Letters Patent No. 682,864, dated September 17, 1901.

Application filed May 2, 1901. Serial No. 58,418. (No model.)

To all whom it may concern:

Be it known that I, CARL WITTKE, a citizen of the United States, residing at Columbus, in the county of Franklin and State of Ohio, 5 have invented a certain new and useful Improvement in Flue-Cutters, of which the following is a specification.

My invention relates to the improvement of flue-cutting devices of that class which are 10 adapted for cutting boiler-flues, pipes, &c.

The objects of my invention are to provide an improved rotary flue-cutting device by means of which a boiler-flue or similar body may be quickly and neatly severed, to provide 15 improved cutter holding and operating mechanism, and to produce other improvements in details of construction and arrangement of parts, which will be more fully pointed out hereinafter. These objects I accomplish 20 in the manner illustrated in the accompanying drawings, in which—

Figure 1 is a view in elevation of my device. Fig. 2 is a longitudinal section on line xx of Fig. 1. Fig. 3 is a plan view of the cutter-carrying lever. Fig. 4 is a sectional view on line zz of Fig. 2, and Fig. 5 is a sectional view taken on two planes as indicated by dotted line yy of Fig. 2.

Similar numerals refer to similar parts 30 throughout the several views.

In carrying out my invention I employ a horizontal cylindrical casing 1, the inner end of which is provided with a disk-like head 2, having a central externally-threaded projection 3. Through the medium of a suitable coupling 4 this projection 3 is connected with one end of a suitably-rotated shaft-section or other rotating body 5. The outer or forward end of the cylinder 1 is formed with an inwardly-flanged or cup ring 12, and on the outer side of the body of the latter is loosely mounted on said arm 8 a collar 13.

14 represents a cutter - lever - controlling stem, the inner unthreaded portion of which passes loosely through the center of the shaft 5 and the cylinder-head projection 3, terminating within the cylinder 1, as shown. The outer threaded portion of the rod or stem 14 has a threaded engagement with an opening in a convenient fixed bracket or engine part 15, which is adjacent to the shaft 5, this threaded outer end of the stem 14 having a suitable handle to facilitate the rotation of the same. The inner end of the stem 14 within the casing 1 is provided with a peripheral recess or continuous groove 16, and about this groove is fitted a sectional collar 17. On the outer side of the collar 17 the stem has loosely mounted thereon an externally-threaded ring 18, with the threads of which engages the internally-threaded socket portion of the arm or stem 19 of a horizontal blade or plate 20, which extends, as shown, 75 within the central portion of the casing 1. Between the end of the socket of said blade-stem 19 and the end of the stem 14 are interposed end-thrust-receiving bearing-balls 21. The rounded upper and lower sides or edges of the blade or plate 20 bear frictionally in upper and lower concaved guide-rollers 22, which are journaled above and below said blade-body. The blade-body 20 is provided, as indicated at 23, with an inclined slotted 80 opening or mortise.

24 represents a cutter-carrying lever, which is in the form of an elongated bar having its central and enlarged portion slotted, as indicated at 25, this slotted portion embracing 90 the blade-body 20. Within the slotted portion of the lever 24 is journaled a roller 26, the latter bearing in the slotted opening 23 of the blade 20. The cutter-carrying lever is angular in form, being shaped to incline upwardly and rearwardly from its roller-carrying portion, terminating in a rearwardly-extending portion 24^a, which is pivoted at 24^b within the rear and upper portion of the casing 1. That portion of the lever 24 which is 95 in front of its roller 26 extends horizontally forward into the slotted opening 9 of the guide

wardly-flanged or cup ring 12, and on the outer side of the body of the latter is loosely mounted on said arm 8 a collar 13.

14 represents a cutter - lever - controlling stem, the inner unthreaded portion of which passes loosely through the center of the shaft 5 and the cylinder-head projection 3, terminating within the cylinder 1, as shown. The outer threaded portion of the rod or stem 14 has a threaded engagement with an opening in a convenient fixed bracket or engine part 15, which is adjacent to the shaft 5, this threaded outer end of the stem 14 having a suitable handle to facilitate the rotation of the same. The inner end of the stem 14 within the casing 1 is provided with a peripheral recess or continuous groove 16, and about this groove is fitted a sectional collar 17. On the outer side of the collar 17 the stem has loosely mounted thereon an externally-threaded ring 18, with the threads of which engages the internally-threaded socket portion of the arm or stem 19 of a horizontal blade or plate 20, which extends, as shown, 75 within the central portion of the casing 1. Between the end of the socket of said blade-stem 19 and the end of the stem 14 are interposed end-thrust-receiving bearing-balls 21. The rounded upper and lower sides or edges of the blade or plate 20 bear frictionally in upper and lower concaved guide-rollers 22, which are journaled above and below said blade-body. The blade-body 20 is provided, as indicated at 23, with an inclined slotted 80 opening or mortise.

24 represents a cutter-carrying lever, which is in the form of an elongated bar having its central and enlarged portion slotted, as indicated at 25, this slotted portion embracing 90 the blade-body 20. Within the slotted portion of the lever 24 is journaled a roller 26, the latter bearing in the slotted opening 23 of the blade 20. The cutter-carrying lever is angular in form, being shaped to incline upwardly and rearwardly from its roller-carrying portion, terminating in a rearwardly-extending portion 24^a, which is pivoted at 24^b within the rear and upper portion of the casing 1. That portion of the lever 24 which is 95 in front of its roller 26 extends horizontally forward into the slotted opening 9 of the guide

8, terminating in outwardly-projecting lugs 27, between which is journaled a wheel-cutter 28.

In utilizing the above-described invention 5 for the purpose of cutting or severing a tube of a boiler the guide extension 8 is inserted within the tube to be cut until the tube abuts against the ring 12, in which position it is obvious that the roller 10 and collar 13 will afford frictional bearings for the guide extension. Rotary motion being contributed to the hollow shaft 5, and hence to the cylinder 1 and the parts contained therein, the stem 14 is turned inward until through the forward 10 movement thereby imparted to the blade 20 and the consequent elevating of the roller 26 and lever 24 the wheel cutter 28 is in proper cutting contact with the inner surface of the tube to be cut. A gradual continuous inward 15 movement of the controlling-stem 14 serves to feed the cutter into the material forming the tube, resulting in the latter being readily severed.

From this construction and operation it will

be seen that simple and positive mechanism 25 is provided for controlling the movement of the cutter-carrying lever and that the rotation of the casing 1 and the parts connected therewith results in a comparative rapid severing of the tube.

Having now fully described my invention, 30 what I claim, and desire to secure by Letters Patent, is—

In a tube-cutter, the combination with a casing or frame, and a horizontally-movable 35 blade 20 having an inclined slotted opening therein, of a lever 24 having a journaled roller bearing in said blade slotted opening, the rear and upper portion of said lever pivoted within said casing or frame and a cutter-wheel 40 journaled in the forwardly-extending portion thereof, means for imparting a rotary motion to the casing and a horizontal movement to the blade 20, substantially as specified.

CARL WITTK.

In presence of—

C. C. SHEPHERD,

FRANCES H. SHEPHERD.
